UNITED STATES PATENT OFFICE.

ALBION D. T. LIBBY, OF ELYRIA, OHIO, ASSIGNOR, BY MESNE ASSIGNMENTS, TO THE GARFORD MANUFACTURING COMPANY, OF ELYRIA, OHIO, A CORPORATION OF OHIO.

COMPOSITE ELECTRIC SYSTEM.

1,137,151.

Specification of Letters Patent. Patented Apr. 27, 1915.

Application filed January 28, 1910. Serial No. 540,572.

To all whom it may concern:

Be it known that I, ALBION D. T. LIBBY, a citizen of the United States, residing at Elyria, in the county of Lorain and State of Ohio, have invented certain new and useful Improvements in Composite Electric Systems; and I do hereby declare the following to be a full, clear, and exact description of the invention, such as will enable others skilled in the art to which it appertains to make and use the same.

My invention relates to a combined police and telephone system, and has for its principal object the improvement of the systems disclosed in companion applications now pending in the United States Patent Office. In the systems of this application I have produced a combination of apparatus in which I may operate lamp signals at the substations over the conductors which are used for telephone purposes, thus reducing the number of conductors.

Other objects of my invention will be clear from the particular description which is to follow, and my invention will be best understood therefrom when taken in connection with the accompanying illustrations showing specific embodiments of such invention, while its scope will be more particularly pointed out in the appended claims.

Figure 1 is a diagram illustrating the preferred form of my invention. Fig. 2 is a diagram of a modification. Fig. 3 is a diagram of a second modification. Fig. 4 is a diagram of a third modification.

Referring now to Fig. 1, I have shown a combined telephone and police system employing the metallic conductors 1 and 2. I also use a third conductor which is here shown as ground. I may employ a metallic conductor in place of ground or may interchange one of the metallic conductors with the ground. At A I show the apparatus which is used at the principal police station, which I shall designate as the main station, and which apparatus is served by an attendant. A number of these combined telephone and police lines radiate from the main station. I have illustrated one of these leading to two patrolmen's boxes, or substations C and D. At the substations I show telephone instruments consisting of a transmitter T, a receiver S in bridge of the line; a high wound polarized relay R⁴ permanently

bridged across the line; a lamp L which is adapted to be connected in a bridge across the telephone line; a police signal sending device E in a conductor legged to ground from a differential point of the polarized relay R⁴; and a grounded key N in the same leg. At the central station I show a relay R³ grounded from the differential point in a bridge of the line. This relay controls the circuit of the register relay R⁵ which in turn controls the police signal receiving and registering device Q. This register is not shown in detail, being the same as that illustrated in a previous application filed by me and being now well known. At R² I show a relay which controls the connection of the lamp operating battery to the conductors 1 and 2. At R¹ I show another relay which controls the automatic disconnection of said source from said line. L² is a pilot lamp which is used to indicate the condition of the lamps at the substations. K² is a key for normally interrupting the circuit of the relay R² when the automatic means is not operated. K¹ is a key for completing a circuit through the relay R² which relay afterwards locks itself upon a second circuit. K is a key for bridging the attendant's telephone set upon the telephone line. L¹ is a line signal which is used to indicate the call of the substation for the attendant. R is a relay which controls this signal and which is energized from a substation over the conductors of the system.

The apparatus and the functions thereof will be best understood from the following description of the operation which is as follows: Suppose a patrolman desires to call the attention of the attendant operator to the telephone circuit. He removes his receiver S from the hook H which moves to close the switch H-3. This closes a circuit as follows: H-T-S-2-4-5-6-7-8-9-battery B¹-relay R-10-11-12-13-14-15-1-3. This energizes the relay R which attracts the armature 16, closing the switch 16-17 and lighting the lamp L¹. Having noticed this, the attendant operates the switch K which opens the switches 11-12 and 7-8, closing the switches 12-18 and 7-19, bridging his set upon the system over the leads 20 and 21. The circuit of the relay R is broken and the lamp extinguished. Suppose that the system be in a normal condition and that the attendant desires to call 110

a patrolman on the beat. He operates the key K¹, closing a circuit as follows: battery B¹—9—22—K¹—23—relay R²—24—back to battery. This energizes R² which pulls up its armature 4, 15 and 25. The armature 25 closes the switch 25—26 and locks the relay R² upon the following circuit: battery B¹—9—K²—27—28—29—26—25—R²—24—back to battery. The attraction of the armatures 4 and 15 breaks the line circuit and bridges the battery B³ thereacross. The relays R⁴ are operated and close the lamp bridges over the following circuit: battery B³—31—4—2—32—R⁴—1—15—30—R¹—back to battery B³. The energization of these relays causes an attraction of their armatures, closing the switch 33—34 in the lamp bridges, and 35—36 in shunts about such lamps. These shunts are still open at 37—38. The lamps are lighted from the battery B³ over the circuits traced for the relay R⁴, except that the current passes through the lamp bridges for the purpose of operating the lamps. It will thus be seen that I both control and operate the lamps over the conductors 1 and 2. The lamps are placed in iron boxes along the beats of the patrolman. Lenses are placed in the surfaces of these boxes. The light radiating through these lenses forms an attractive signal which can be seen from a great distance. The attention of the patrolman having been attracted, he proceeds to the box, opens the same, and takes his receiver from the hook. The spring pressed hook moves to close the switch 11—3, but before the switch is closed and before the telephone instrument is placed in bridge of the conductors, the rising hook closes a flash switch 37—38. The closure of this switch shunts the lamp L and the relay R⁴ making a low resistance bridge across the line. As long as the resistance of the lamps L and the relay R⁴ were in the circuit of relay R⁴ the current from battery B³ was insufficient to operate the same. The interposition of the low resistance shunt 40 allows enough current to flow through R¹ to operate the same. Relay R¹ pulls up its armature 29, breaking the circuit of relay R² at 28—29. Relay R² being deenergized, the armatures 4, 15 and 25 return to their normal positions as shown in the drawing. This interrupts the locking circuit of R² and disconnects the lighting source B³ from the line conductors. This source having been removed, the relays R⁴ are deenergized, the lamps extinguished and the shunt 40 broken at 35—36. The hook switch passes on over the contact 37—38, closing switch 11—3, when telephone conversation may be carried on over the circuit previously described. I have thus produced a system in which I use the telephone conductors for lighting purposes and in which the source of lighting current is automatically disconnected from

the line by the operation of the hook switch at the substation and is disconnected before the telephone instruments are cut in upon the line. I thus prevent any interference between the operation of the lamps and the telephoning. To send in a police signal such as are generally sent in at certain intervals, the signal sending apparatus E is operated by the patrolman which acts to make and break the circuit from ground G²—E—41—70 to a point in the center of the winding of the relay R⁴—through the two parts of this winding in parallel—to the conductors 1 and 2—through the parts of the shunt 32, in parallel—through the conductors 1 and 2 80 in parallel—through the parts of a bridge 42 at the main station—through the two resistance coils V therein to a neutral point, the leg 43—the relay R²—battery B²—to ground G¹. The resistances of the coils V, V are so great that neither the telephone nor the lamp controlling nor operating currents pass therethrough. The resistance of the windings of the relay R⁴ is so great that after the lamp bridges have been closed, only current 85 enough passes therethrough to hold up the armatures, the major part of the current being diverted through the lamps. The switches N are for the purpose of sending a special signal to the police signal receiving apparatus at the main station, and operate over substantially the same circuit as that which is described. In other words, the relay R³ pulls up its armature 45, closing the switch 45—46 in the circuit of the register 100 relay R⁵ which operates the register mechanism. The relay R will not operate through the bridges of the resistance device V, V nor through the relays R⁴, not enough current flowing therethrough to operate this relay. 105 The relay R³, however, is capable of operating through the combined resistance of R⁴ and V when placed in the circuit of said relay as described in the circuit traced.

In the modification shown in Fig. 2 the 110 lamps L are connected in series with the condensers C¹ and low resistance, high impedance coils 100, and the three bridged across the line at each substation. The impedance coils 100 serve to prevent the passage of voice currents through the bridges, the condensers C¹ serving to permit the passage of alternating currents at the same time barring the passage of continuous currents. The police signal sending apparatus E and the special police signal sending switch N are connected substantially the same as in Fig. 1, and are legged to ground from the conductor 2. Special switches M are provided for the operation of the line signal 115 at the main station, the control of this signal being removed from the telephone set. The circuit of this is traced from M—through 1—15—14—13—12—11—relay R—battery B—to ground G. At the substation the 120

police signal receiving and registering apparatus is connected to the side 2 of the line, the circuit therethrough being traced from E or N—41—2—4—5—6—7—8—9—battery

- 5 B¹—to ground. The lamp signal operating current is furnished by an alternator X which is connected to the line by a relay R², and automatically disconnected by relay R¹ when response is made at a substation.
- 10 This arrangement and the operation thereof is substantially the same as shown in Fig. 1, and the description need not be repeated here.

In the modification shown in Fig. 3 I provide a special line signaling circuit for calling the main station attendant from the substations. This consists in the switches M and the conductor 101. The lamps at the substations are bridged across the line with 20 a retardation coil C, C¹ on each side thereof. These coils serve two functions: first, they balance the lamps; that is, their resistance may be changed to compensate for the resistance in the lines which is caused by the 25 nearness or remoteness of the lamps to the source or operating current; and second, they serve to retard the voice currents, preventing their flow through these bridges. The police signal sending apparatus E and 30 the special signal sending apparatus N are legged from the center point of these coils to ground. The police signal sending circuit operates over the conductors 1 and 2 in phantom which, in this case, means that they 35 operate in multiple over these conductors and return through ground. In the circuit of the battery B³ which furnishes the lamp signal operating current I place a galvanometer I to indicate the amount of current 40 flowing through the lamp circuit which is evidence of the number of lamps upon the circuit in operative condition. In this circuit no automatic means is provided for disconnecting the lamp operating source, 45 the system depending upon the patrolman's pressing the button M to signal the attendant that he is about to respond. The attendant then manually disconnects the source.

50 In Fig. 4 I show in place of the galvanometer I a lamp L² shunted by a low resistance V¹ for the same purpose. In this circuit I show an armature 102 for the line relay R. This armature is one of the elements of switch 102—103 in the circuit of the lamp signal operating source. When the patrolman operates the key M in response to the signal, the relay R is energized interrupting the circuits of this source and taking it from the line. The operator observing the signal L¹ opens the switch K¹ and restores the line connection through to the key K.

55 In these circuits I have produced in a combined police and telephone system,

among other things, a 2-metallic conductor system over which telephoning, police signaling from the substations to the attendant station and signaling from the attendant station to the patrolman's beat may be accomplished without interference among the various currents which are necessary in the transmission of these various forms of communication. The pilot lamps also serve the purpose of notifying the operator that response has been made at a called station should the line lamp fail to accomplish this.

70 I have shown these particular embodiments of my invention, as they very clearly illustrate the same, but I do not wish to be limited to these forms. It will be obvious to those skilled in the art that numerous and extensive departures from them and the details of the apparatus here shown—may be made without departing from the spirit of 85 this invention. The particular scope of the invention which I claim is more especially pointed out in the appended claims.

I claim:

1. In a composite system consisting of a 90 combined police and telephone system, the combination of a main station and a plurality of substations, conductors connecting said stations, telephone instruments connected to two of said conductors and adapted to be operated thereover, low-resistance non-inductive lamp signals at said substations, non-inductive means for connecting said lamps in circuit with said telephone conductors, said lamps operating thereover, 95 a source of current adapted to be connected in circuit with said telephone conductors to actuate said signals and means for automatically disconnecting said source when response is made at a signaled substation. 100

2. In a composite system consisting of a 105 combined police and telephone system, the combination of a main station and a plurality of substations, conductors connecting said stations, telephone instruments connected to two of said conductors and adapted to be operated thereover, lamp signals at 110 said substations, means for connecting said lamps in circuit with said telephone conductors, said lamps operating thereover, a 115 source of current, means for connecting said source in circuit with said telephone lines and said signals, and means for automatically interrupting said connection when response is made at a signaled station, said 120 means operating before the telephone at that station is connected in circuit with said conductors.

3. In a composite system consisting of a 125 combined police and telephone system, the combination of a main station and a plurality of substations, conductors connecting said stations, telephone instruments connected to two of said conductors and adapted to be operated thereover, lamp signals at 130

- 5 said substation, means for connecting said lamps in circuit with said telephone conductors, said lamps operating thereover, a source of current for operating said signals, 10 means for connecting said source in circuit with said telephone conductors and said signals, and means for disconnecting said source from said conductors before the telephone instrument at a substation is connected in circuit therewith.
- 10 4. In a composite system, consisting of a combined police and telephone system, the combination of a main station and a plurality of substations, conductors connecting 15 said stations, telephone instruments at said substations connected to two of said conductors, lamp signals at said substations, a source of current adapted to operate said lamp signals, means for connecting said source in circuit with said telephone conductors, a normally open shunt of said conductors and means to automatically close said shunt when response is made at a signaled substation, the closure of said shunt occurring before the telephone instrument is connected to the line and operating to cause disconnection of said source from said conductors.
- 15 5. In a composite system consisting of a combined telephone and police system, the combination of a main station, a plurality of substations, conductors connecting said stations, telephone instruments operating over a pair of said conductors, a police signaling system operating in phantom over said conductors and low resistance, non-inductive lamp signals at said substations adapted to be connected in circuit with said telephone conductors and to be operated 20 thereover.
- 20 6. In a composite system consisting of a combined telephone and police system, the combination of a main station, a plurality of substations, conductors connecting said stations, telephone instruments utilizing two of said conductors, a police signaling apparatus operating over said telephone conductors, means to prevent interference between said telephone and police signal transmission over said conductors whereby telephoning and police signaling may occur simultaneously, lamp signals at the substations adapted to be operated over said telephone conductors, and means for connecting said signals in circuit with said conductors.
- 25 7. In a composite system consisting of a combined telephone and police system, the combination of a main station, a plurality of substations, conductors connecting said stations, telephone instruments utilizing two of said conductors, a police signaling apparatus operating over said telephone conductors, means to prevent interference between said telephone and police signal transmission over said conductors whereby telephon-
- 30 ing and police signaling may occur simultaneously, lamp signals at the substations adapted to be operated over said telephone conductors, means for connecting said signals in circuit with said conductors, and means to prevent the simultaneous connection of said lamp signals and said telephone instruments to said telephone conductors.
- 35 8. In a composite system consisting of a combined telephone and police system, the combination of a main station, a plurality of substations, conductors connecting said stations, telephone instruments operating over certain of said conductors, police signaling instruments operating over certain of said conductors, and low resistance, non-inductive lamp signals at said substations, a non-inductive circuit therefor, one of said conductors common to said telephone, police signaling and lamp signal circuits.
- 40 9. In a composite system consisting of a combined telephone and police system, the combination of a main station, a plurality of substations, conductors connecting said stations, telephone instruments operating over certain of said conductors, police signaling instruments operating over certain of said conductors, lamp signals at said substations, a circuit therefor, one of said conductors common to said telephone, police signaling and lamp signal circuits, and means to prevent interference among the transmission over said several circuits.
- 45 10. In a composite system consisting of a combined police and telephone system, the combination of a main station, a plurality of substations, a pair of conductors connecting said stations, telephone instruments at said substations adapted to be connected in bridge of said conductors and to operate thereover, police signaling apparatus for sending signals to the main station operating over said conductors in multiple, lamp signals at said substations, and means controlling said signals connected to be operated over said conductors.
- 50 11. In a composite system consisting of a combined police and telephone system, the combination of a main station, a plurality of substations, a pair of conductors connecting said stations, telephone instruments at said substations adapted to be connected in bridge of said conductors and to operate thereover, police signaling apparatus for sending signals to the main station operating over said conductors in multiple, lamp signals at said substations adapted to be operated over said conductors, and means controlling the connection of said signals to said conductors.
- 55 12. In a composite system consisting of a combined police and telephone system, the combination of a main station, a plurality of substations, a pair of conductors connecting said stations, telephone instruments at

- said substations adapted to be connected in bridge of said conductors and to operate thereover, police signaling apparatus for sending signals to the main station operating over said conductors in multiple lamp signals at said substations adapted to be connected to said conductors, a source of current and means to connect said source in circuit with said lamps.
- 10 13. In a composite system consisting of a combined police and telephone system, the combination of a main station and a plurality of substations, a pair of conductors connecting said stations, telephone instruments adapted to be connected in bridge of
- 5 said line, police signal sending and receiving apparatus adapted to operate over said conductors in multiple, lamp signals at the substations adapted to be operated over said conductors, and means to prevent the simultaneous connection of said telephone instruments and said lamp signals to said conductors.
- 15 In testimony whereof I affix my signature in presence of two witnesses.
